UNITED STATES PATENT OFFICE

HERBERT E. TAUTZ, OF MILWAUKEE, WISCONSIN, ASSIGNOR TO DELTA MANUFACTURING COMPANY, OF MILWAUKEE, WISCONSIN

DESIGN FOR A GAUGE

Application filed September 24, 1932. Serial No. 45,059. Term of patent 14 years.

To all whom it may concern:

Be it known that I, HERBERT E. TAUTZ, a citizen of the United States, residing at 3775 North Holton Street, Milwaukee, in the county of Milwaukee and State of Wisconsin, have invented a new, original, and ornamental Design for Gauges, of which the following is a specification, reference being had to the accompanying drawing, forming part thereof.

The figure is a perspective view of a gauge, showing particularly the appearance of the upper surface of the same, embodying my new design.

I claim:

The ornamental design for a gauge, as shown and described.

HERBERT E. TAUTZ.
